HORS D'OEUVRES SERVER OR SIMILAR ARTICLE

Francis L. Haskell, Bristol, Conn., assignor to Associated Spring Corporation, Bristol, Conn., a corporation of Delaware

Application August 18, 1955, Serial No. 37,555

Term of patent 14 years

(Cl. D44—15)

Fig. 1 is a side view of an hors d'oeuvres server or similar article showing my new design;

Fig. 2 is a top plan view of the server shown in Fig. 1;

Fig. 3 is a front end view, and

Fig. 4 is a rear end view.

I claim:

The ornamental design for an hors d'oeuvres server or similar article, as shown.
